(57) **ABSTRACT**

'NCORNSP-030ILPL' is a moderately compact and loosely upright variety of *Ipomoea batatas* with a moderate growth rate and is well branched. It is distinguishable from other ornamental sweetpotato cultivars by its burgundy palmate, very deeply lobed leaves with 5-7 lobes, a moderately-compact habit and semi-erect mounding plant architecture. The burgundy leaves, very deep lobing, short internodes, and the plant architecture, which promotes good plant production in the greenhouse for wholesale distributors, distinguishes 'NCORNSP-030ILPL' amongst the current ornamental sweetpotatoes in the marketplace. 'NCORNSP-030ILPL' has been shown to be less vigorous than *Ipomoea batatas* 'Margarita' and 'Mackie' and is suitable for use as a landscape or containerized plant.

6 Drawing Sheets

1

Latin name of the genus and species: The Latin name of the novel, ornamental plant variety disclosed herein is *Ipomoea batatas* (L.) Lam.

Variety denomination: The inventive cultivar of *Ipomoea batatas* disclosed herein has been given the varietal denomination 'NCORNSP-030ILPL'.

BACKGROUND OF THE INVENTION

Ipomoea batatas is a member of the morning glory family Convolvulaceae. This species is grown worldwide and it exhibits a wide range of plant forms and colors. The cultivated members of *Ipomoea batatas* grown by farmers worldwide are commonly produced for consumption of their nutritious, enlarged storage roots. These types typically produce a fast growing green vine that has a wide variety of leaf shapes ranging from palmate and deeply lobed, to cordate or triangular shaped leaves with no lobes.

Like their edible forms, *Ipomoea batatas* ornamental sweetpotato plants are a heat-loving, drought-tolerant, perennial vine typically grown as an annual. However, ornamental sweetpotato plants are distinguished from the edible cultivated forms in that they often do not produce attractive, enlarged storage roots suitable for human consumption. Instead, they possess unique foliage colors, leaf shapes, and growth habits, which have significant value in the ornamental marketplace.

Ornamental sweetpotatoes are desirable in the landscape and ornamental industries because their foliage comes in a wide variety of colors (e.g., pale yellow to dark purple with some exhibiting temporal and individual leaf color variegation patterns) and plant shapes (e.g., mounded and very

2

compact to prostrate and highly spreading). They can be grown in a potted plant and/or mixed planting format, and they have the ability to cover a large space or hang over walls and decorative pots creating brightly colored and textured backdrops in gardens and patios. Most ornamental sweetpotatoes grow and last the entire growing season and they require little maintenance. Moreover, these plants have few insect or disease problems.

10 To meet the growing horticultural demand for ornamental sweetpotatoes, it is desirable to produce new cultivars of ornamental sweetpotato with new or improved foliage colors, variegation patterns, leaf shapes, and plant architectures. In addition, it would be advantageous to develop cultivars of 15 ornamental sweetpotato exhibiting a more compact growth that do not out-compete other species in mixed containers.

'NCORNSP-030ILPL' was bred to meet the demand for new ornamental sweetpotatoes. 'NCORNSP-030ILPL' is a moderately compact and loosely upright variety with a moderate growth rate and is well branched. It is distinguishable from other ornamental sweetpotato cultivars by its burgundy palmate, very deeply lobed leaves with 5-7 lobes, a moderately-compact habit and semi-erect mounding plant architecture. The burgundy leaves, very deep lobing, short internodes, and the plant architecture, which promotes good plant production in the greenhouse for wholesale distributors, distinguishes 'NCORNSP-030ILPL' amongst the current ornamental sweetpotatoes in the marketplace. In greenhouse and field trials conducted since 2019 by the breeding program and industry collaborators 'NCORNSP-030ILPL' has been shown to be less vigorous than *Ipomoea batatas* 'Margarita' and 'Blackie' and is suitable for use as a land-

scape or containerized plant. The production of flowers by 'NCORNSP-030ILPL' is sporadic under short day conditions.

Lineage. 'NCORNSP-030ILPL' (breeding designation NC10287-074ORN) originated from hand-pollinated seed from the proprietary *Ipomoea batatas* breeding lines NC8818-076ORN (the female parent; not patented) and NC8213-005ORN (the male parent; not patented). Botanical seed was harvested from ornamental lines grafted onto a flower-inducing *I. setosa* sweetpotato line in greenhouses between October 2017 and April 2018 in Raleigh, N.C. NC8818-076ORN resulted from open-pollinated seed harvested from the proprietary *Ipomoea batatas* breeding line NC4718-002ORN (the female parent; not patented). NC8213-005ORN resulted from open-pollinated seed collected from NC6176-002ORN (the female parent; NCORNSP-013GNLC, U.S. Plant Pat. No. 23,612). Botanical seed from this family were planted in the greenhouse in December 2018. The first cycle of selection on the population was exercised at the seedling tray stage and each survivor was transferred to a single 6-inch pot, which was then maintained in the greenhouse. Cuttings (2 each) were taken from the plants in April and planted in the field as unreplicated 2-plant plots, during mid-June 2019. The single, individual plant now known as 'NCORNSP-030ILPL' was selected Sep. 25, 2019 because of its combination of exceptional features, and it has been propagated asexually since that time.

Asexual Reproduction. Since its selection, *Ipomoea batatas* 'NCORNSP-030ILPL' has been asexually reproduced in Raleigh, N.C. predominantly by vegetative propagation of vine cuttings. Successively, there have been five cycles of vegetative propagation, one cycle of tissue culture micro-propagation, and multiple vegetative propagation cycles to increase plant numbers. Asexual reproduction of 'NCORNSP-030ILPL' by cuttings has shown that the unique features of the new cultivar are stable and the plant reproduces true to type in successive generations.

SUMMARY OF THE INVENTION

'NCORNSP-030ILPL' was bred to meet the increasing demand for new ornamental sweetpotatoes. 'NCORNSP-030ILPL' is a moderately compact and loosely upright variety with a moderate growth rate and is well branched. It is distinguishable from other ornamental sweetpotato cultivars by its burgundy palmate, very deeply lobed leaves with 5-7 lobes, a moderately-compact habit and semi-erect mounding plant architecture. The burgundy leaves, very deep lobing, short internodes, and the plant architecture, which promotes good plant production in the greenhouse for wholesale distributors, distinguishes 'NCORNSP-030ILPL' amongst the current ornamental sweetpotatoes in the marketplace. In greenhouse and field trials conducted since 2019 by the breeding program and industry collaborators 'NCORNSP-030ILPL' has been shown to be less vigorous than *Ipomoea batatas* 'Margarita' and 'Blackie' and is suitable for use as a landscape or containerized plant. The production of flowers by 'NCORNSP-030ILPL' is sporadic under short day conditions.

BRIEF DESCRIPTION OF THE DRAWINGS

The photographs in the drawings were made using conventional techniques and show the colors as true as reasonably possible by conventional photography. Colors in the

photographs may differ slightly from the color values cited in the detailed botanical description, which more accurately describe the colors of the new *Ipomoea batatas*.

FIG. 1 is a color photograph of a typical specimen of 5 greenhouse grown *Ipomoea batatas* 'NCORNSP-030ILPL' in a 6-inch pot from the side, 50 days after planting.

FIG. 2 is a color photograph of a typical specimen of 10 greenhouse grown *Ipomoea batatas* 'NCORNSP-030ILPL' in a 6-inch pot from the top, 50 days after planting.

FIG. 3 is a color photograph of a typical specimen of 15 *Ipomoea batatas* 'NCORNSP-030ILPL' from the side in the field, 75 days after planting.

FIG. 4 is a color photograph of a typical specimen of 20 *Ipomoea batatas* 'NCORNSP-030ILPL' from the top in the field, 75 days after planting.

FIG. 5 is a color photograph showing the upper (top) and 25 lower (bottom) surfaces of mature leaves produced by 20 greenhouse grown *Ipomoea batatas* 'NCORNSP-030ILPL', 50 days after planting.

FIG. 6 is a color photograph showing the storage roots produced by 30 *Ipomoea batatas* 'NCORNSP-030ILPL' in the field, 134 days after planting.

DETAILED BOTANICAL DESCRIPTION OF 35 THE NEW VARIETY

The following is a detailed description of the botanical characteristics of a new and distinct cultivar of *Ipomoea batatas* plant known by the cultivar name 'NCORNSP-030ILPL'. All colors cited herein refer to The Royal Horticulture Society Colour Chart designations (The Royal Horticultural Society, London, 1995, 4th ed.) except where general terms of ordinary dictionary significance are used. Plant descriptions are based on the standardized international sweetpotato descriptors established jointly by the International Potato Center (CIP), Lima, Peru; The Asian Vegetable Research and Development Center (AVRDC), Taipei, Taiwan; and the International Board for Plant Genetics Resources (IBPGR), Rome, Italy (CIP, AVRDC, IBPGR. 40 1991. Descriptors for Sweet Potato. Huaman, Z., editor. International Board for Plant Genetic Resources, Rome, Italy, 134pp.). Where dimensions, sizes, colors, and other 45 characteristics are given, it is to be understood that such characteristics are approximations or averages set forth as accurately as practicable.

The descriptions reported herein are from a group of 50-day-old specimens grown individually in six-inch azalea pots. The plants were grown in Raleigh, N.C., under commercial practice in a glass-covered greenhouse, where, during the fall, day and night temperatures range between 30-40° C. and 22-26° C., respectively. After rooting, plants were treated with 200 ppm N 20-10-20 fertilizer weekly. Plant histories were taken in October 2021 in Raleigh, N.C. 55 *Ipomoea batatas* 'NCORNSP-030ILPL' has not been observed under all possible environmental conditions; therefore, the phenotype may vary under different environmental conditions such as season, temperature, light intensity, day length, cultural conditions, and the like, without however, 60 any variance in the genotype.

Classification:

Botanical name.—*Ipomoea batatas* (L.) Lam.

Common name.—Ornamental Sweetpotato.

Variety name.—'NCORNSP-030ILPL'.

Growth conditions: *Ipomoea batatas* 'NCORNSP-030ILPL' has very good vigor and a moderate growth rate. In

locations with mild winter conditions, *Ipomoea batatas* 'NCORNSP-030ILPL' will grow perennially; otherwise, it is an annual plant. Similar to other cultivated sweet-potatoes, wind or rain rarely cause much damage to 'NCORNSP-030ILPL', but if damage does occur, the plant drops the damaged leaves and grows new shoots at nodes where the leaves were lost. Under low light levels in a greenhouse, 'NCORNSP-030ILPL' can develop intumescence, which will remain on the affected foliage, but will be outgrown with new foliage.

Aboveground structure and coloration: FIGS. 1, 2, 3, 4, and 5 show the shape and coloration of a typical specimen of *Ipomoea batatas* 'NCORNSP-030ILPL'. Color may vary somewhat due to temperature and nutrient stress. Overall, this cultivar is a moderately-compact, non-twining, semi-upright herbaceous plant that has an average height of about 20.3 cm and an average area spread of about 59.9 cm. The growth habit of this plant is to grow upright with shoots growing upward and outward.

Branches:

Branching habit.—Freely-branching with about 3-4 primary lateral branches coming off the stem. Very dense foliage and no pinching is required to stimulate branching. Branch texture is slightly pubescent.

Vegetative lateral branching.—Length: about 16.9 cm. Diameter: about 0.5 cm. Internodes are short with an average length of about 2.2 cm.

Secondary lateral shoots.—No measurable secondary lateral shoots formed on the rated plants.

Stem.—Round and smooth with an upward, very strong, slightly flexible, non-brittle strength. Primary color: greyed-purple (RHS 187A).

Adventitious roots.—Greyed-green (RHS 196C).

Foliage: Leaves are alternate and tend to slightly spiral around the stem. They are simple and heavily divided into 5-7 lobes. Leaf shape is somewhat variable as is size. (see FIG. 5).

Quantity.—Heavily foliated, with about 25.8 leaves per lateral branch.

Mature leaf length.—About 12.8 cm.

Mature leaf width.—About 15.1 cm.

Leaf margin.—Entire.

Leaf apex.—Apiculate.

Leaf base.—Auriculate.

Leaf texture.—Glabrous texture and matte finish.

Venation.—Arcuate to cross-venulate.

Color.—Leaves are greyed-purple (RHS 187A) and range within that palate as they mature. See also Table 1.

Petiole.—Petioles are held slightly upward and curve outward. Leaf petiole has slight pubescence. Length: about 11.6 cm. Diameter: about 0.2 cm. Primary color: greyed purple (RHS 187B), secondary color: purple (RHS N79C).

TABLE 1

Leaf color of <i>Ipomoea batatas</i> 'NCORNSP-030ILPL'.		
Leaf Structure	Upper Surface	Lower Surface
Mature Leaf	Greyed-Purple (RHS 187A)	Purple (RHS N79B)
Young Leaf	Yellow-Green (RHS N144A)	Yellow-Green (RHS 144D)
Vein- mature leaf	Greyed-Purple (RHS N187A)	Purple (RHS N79C)

TABLE 1-continued

Leaf color of <i>Ipomoea batatas</i> 'NCORNSP-030ILPL'.		
Leaf Structure	Upper Surface	Lower Surface
Vein -young leaf	Yellow-Green (RHS 144A)	Purple (RHS N78D)

Inflorescence: The production of flowers by 'NCORNSP-030ILPL' is very sporadic and mostly observed under stressful conditions (e.g., drought, nutrient stress, cloudy weather). Shorter day lengths enhance flowering, but the precise photoperiod for flower induction is currently unknown. Solitary, regular funnel-form flowers arising from leaf axils on secondary lateral branches are formed. Peduncles are purple (RHS N79B). Peduncle length: about 2.8 cm, peduncle diameter: about 0.2 cm. Flower buds are purple (RHS 76B-76D) and elliptic. Limb color: cream (RHS 155A) on the outer surface and inner surfaces. The outer throat color begins purple (RHS 77D) and gradually lightens towards the limb. The limb is pentagonal to rounded with slight fragrance. Corolla length: about 4.0 cm, corolla width: about 4.3 cm. The flower averages five sepals. The outer sepals are shorter than the inner sepals. Average outer sepal length: about 1.0 cm, average outer sepal width: about 0.4 cm, average inner sepal length: about 1.1 cm, average inner sepal width: about 0.4 cm. The sepals are elliptic with an obtuse apex and smooth margins and are yellow-green (RHS 145B) in color. A single pistil consists of one style and one stigma about 2.3 cm in length. Stigma and style are both cream (RHS 157A). The stigma is exerted relative to the stamens. The flower averages five stamens. Pollen color: cream (RHS 155A). Pollen is profuse. Fruit has not been observed under normal greenhouse conditions.

Storage root coloration: *Ipomoea batatas* 'NCORNSP-030ILPL' forms no, to small, underground storage roots that are typically malformed and do not meet USDA Sweetpotato Storage Root Grade Standards (see FIG. 6). Fibrous roots are typically cream (RHS 155B). Storage roots that are formed possess red (RHS 49C) skin with a yellow-white (RHS 158B) primary flesh color and yellow-white (RHS 160D) secondary flesh color.

Disease or pest resistance: 'NCORNSP-030ILPL' is susceptible to whiteflies and thrips in a greenhouse environment. 'NCORNSP-030ILPL' is susceptible to damage by Japanese beetles under outdoor conditions. The susceptibility of 'NCORNSP-030ILPL' to other known insects and pathogens of sweetpotato is unknown. Under low light conditions, slight edema may occur.

Comparison with other *Ipomoea batatas* cultivars: 'NCORNSP-030ILPL' is distinct based on leaf size, plant habit, color uniformity, and lobing. Of the common cultivars of ornamental sweetpotato, 'NCORNSP-030ILPL' is best compared with the 'NCORNSP-013GNLC' (U.S. Plant Pat. No. 23,612) and 'NCORNSP-026SCRH' (NC-8998-002OSP, unpatented) cultivars (Table 2). Like both 'NCORNSP-013GNLC' and 'NCORNSP-026SCRH', 'NCORNSP-030ILPL' has burgundy leaves. 'NCORNSP-030ILPL' has larger leaves on average than 'NCORNSP-013GNLC'. Additionally, the color uniformity of 'NCORNSP-030ILPL' is more consistent throughout the season than either 'NCORNSP-013GNLC' or 'NCORNSP-026SCRH'. 'NCORNSP-030ILPL' also has a loosely upright habit, while 'NCORNSP-013GNLC' has a trailing habit. The deeper

lobing and greater lobe number of 'NCORNSP-030ILPL' are the most noticeable contrast between it and 'NCORNSP-026SCRH'.

'NCORNSP-030ILPL' is distinct from its parents, NC8818-076ORN and NC8213-005ORN, by its lobing, habit, branching, color and growth rate. 'NCORNSP-030ILPL' has noticeably deeper sinuses than either NC8818-076ORN or NC8213-005ORN. It is more compact with more frequent branching than NC8818-076ORN. Additionally, 'NCORNSP-030ILPL' is lighter in color than NC8213-005ORN, and it is also more vigorous in both field and greenhouse settings.

TABLE 2

Comparison of 'NCORNSP-030ILPL' with other *Ipomoea batatas* cultivars.

Characteristic	'NCORNSP-030ILPL'	'NCORNSP-013GNLC'	'NCORNSP-026SCRH'
Plant Habit	Moderately compact, loosely upright habit	Moderately compact, trailing habit	Moderately compact, semi-erect mounding habit

TABLE 2-continued

Comparison of 'NCORNSP-030ILPL' with other *Ipomoea batatas* cultivars.

Characteristic	'NCORNSP-030ILPL'	'NCORNSP-013GNLC'	'NCORNSP-026SCRH'
Average Leaf Length and Width	Length: 12.7 cm Width: 15.1 cm	Length: 7.9 cm Width: 7.8 cm	Length: 9.6 cm Width: 10.4 cm
Foliage Color	Greyed-purple (RHS 187A)	Greyed-purple (RHS 187A)	Greyed-purple (RHS 187A)
Leaf Shape	Very deeply lobed, 5-7 lobes. Entire with an apiculate apex and an auriculate base.	Very deeply lobed, 5-7 lobes. Entire with an apiculate apex and a cordate base.	Moderately lobed, 3-5 lobes. Entire with an apiculate apex and a cordate base.

We claim:

1. A new and distinct cultivar of *Ipomoea batatas* plant 20 named 'NCORNSP-030ILPL', substantially as illustrated and described herein.
